UNITED STATES PATENT OFFICE.

JOHN KERR, OF TORONTO, ONTARIO, CANADA.

NON-REFILLABLE BOTTLE.

1,305,549.

Specification of Letters Patent. Patented June 3, 1919.

Application filed October 12, 1917. Serial No. 196,286.

To all whom it may concern:

Be it known that I, JOHN KERR, a subject of the King of England, residing at Toronto, Province of Ontario, and Dominion of Canada, have invented new and useful Improvements in Non-Refillable Bottles, of which the following is a specification.

The invention relates to improvements in non-refillable bottles as described in the 10 present specification and shown in the accompanying drawings that form part of the same.

The invention consists essentially of the novel construction of the neck of the bottle 15 whereby a ball valve is movably secured therein adjacent to the lower end and whereby a plurality of overlapping baffle walls projecting inwardly from opposite sides of the wall of the neck form a protection for 20 said valve from above.

The objects of the invention are to provide a non-refillable bottle from which the contents can be poured quite freely but into which it will be impossible to force any 25 liquid thus preventing the refilling of bottles from which the original contents have been withdrawn, and generally to produce a non-refillable bottle which will be inexpensive to manufacture and secure.

30 In the drawings Figure 1 is a vertical sectional view through the neck of the bottle.

Fig. 2 is a vertical sectional view through the neck of the bottle taken on the line A—A of Fig. 1.

35 Fig. 3 is a cross sectional view on the line B—B of Fig. 1.

Fig. 4 is a cross sectional view on the line C—C of Fig. 1.

Like numerals of reference indicate 40 corresponding parts in each figure.

Referring to the drawings, 1 is the upper portion of the body of a bottle converging to the narrow central opening 2 and having the neck 3 extending upwardly therefrom in 45 an elongated outward flare and merging into an intermediate globe portion 4 terminating in the cylindrical upper end 5, said neck adjacent to its lower end having the slightly curved portion 6 forming a seat for the ball 50 valve 7.

8 and 9 are baffle walls extending inwardly from opposite sides of the globe portion 4, said baffle walls being arranged one above the other and extending almost entirely across the opening through the neck 55 of the bottle and overlapping each other.

10 and 11 are bosses projecting inwardly from opposite sides of the neck 3 a short distance below the globe portion 4 and forming a stop for the ball valve 7 when the 60 bottle is inverted.

12 is an annular ring around the neck 3 above the globe portion 4 to which may be secured any suitable seal.

13 is a fine wire secured to the ball valve 7 65 and extending upwardly through the neck 3 to facilitate the raising of said valve from its seat prior to pouring the original contents into the bottle, said wire being sufficiently fine adjacent to its engagement with 70 the valve 7 to be easily broken after the bottle is filled.

It will be seen that the bottle can be easily filled so long as the wire 13 is secured to the valve 7 and said valve can be held 75 midway between the bosses 10 and 11 and the valve seat 6 but as soon as the wire is broken the valve drops into its seat and chokes the entrance to the bottle. Owing to the overlapping arrangement of the baffle 80 walls it will be impossible to gain access to the valve 7 to hold it from its seat while the bottle is in its upright position and of course when the bottle is inverted it will be impossible to force any liquid 85 thereinto past the said walls but if by any chance any liquid should pass said walls it will strike the valve and force it to its seat again and close the entrance to the bottle.

By simply tipping the bottle sufficiently to 90 allow the liquid to flow through the opening 2 the said liquid will pour freely from the bottle.

It will be observed that the baffle wall 8 curves slightly toward the open mouth of 95 the neck while the baffle wall 9 is so positioned below the former wall that the facing surfaces of the two are substantially parallel throughout their length. Since the baffle wall 8 is inclined slightly upward, the 100 path of flow of a liquid leaving the bottle is thus always from a higher to a lower point. This arrangement provides for emptying the bottle of all its contents and avoids danger of trapping any of the contents behind the baffle walls.

Again, the neck is enlarged in the vicinity of the baffle walls and the free ends of these walls terminate in this enlargement beyond imaginary lines drooped from the inside 110 walls of the cylindrical upper end 5 directly above these free ends. Thus, an instrument

to be inserted around the free end of the baffle wall 8 must be inclined away from the side wall of the upper portion 5 standing directly above this free end of the baffle plate. Therefore, such an instrument or wire would be inclined at an angle such as would make it impossible to direct the end of the wire around in the space between the two baffle walls.

10 What I claim is:

In a non-refillable bottle, a neck having a cylindrical upper end open at the top, this cylindrical end merging into an intermediate globular portion, the neck thereafter tapering in shape and terminating in a restricted portion forming a ball valve seat, said globular portion having opposed overlapping baffle walls the free ends of which terminate beyond imaginary lines dropped 15 from those inside walls of the cylindrical portion directly above the said free ends, the upper baffle wall inclining slightly upward and being uniformly spaced throughout its 20

length from the lower baffle wall, whereby a liquid in passing through the neck moves 25 always from a higher to a lower level to prevent trapping of the liquid behind the baffle walls, the cylindrical end being unobstructed between said imaginary lines above said baffle walls, the tapering portion of the 30 neck having diametrically opposed inwardly projecting tongues, and a ball valve engageable upon the said ball valve seat to close communication between the bottle and the neck, the said valve being also engageable upon the tongues when the bottle is in inverted position at which time a liquid may pass freely around the ball in flowing through the neck.

Signed at Toronto, Ont., this ninth day of 40 October, 1917.

JOHN KERR.
